UNITED STATES PATENT OFFICE

135,200

DESIGN FOR A TOY ANIMAL

Katharine R. Geis, Anne Arundel County, Md.

Application January 25, 1943, Serial No. 109,339

Term of patent 7 years

To all whom it may concern:

Be it known that I, Katharine R. Geis, a citizen of the United States and a resident of Anne Arundel County, State of Maryland, have invented a new, original, and ornamental Design for a Toy Animal, of which the following is a specification, reference being had to the accompanying drawing, forming part thereof.

In the drawing:

Fig. 1 is a side elevational view of the toy animal, showing my new design.

Fig. 2 is a view of the toy animal in perspective looking from a right frontal direction; and

Fig. 3 is a rear elevational view of the same.

I claim:

The ornamental design for a toy animal, substantially as shown.

KATHARINE R. GEIS.
